UNITED STATES PATENT OFFICE.

FRANK E. STAIR, OF SOUTH BEND, INDIANA.

DESIGN FOR A LAMP.

53,944.

Specification for Design.

Patented Oct. 7, 1919.

Application filed June 26, 1919. Serial No. 307,024. Term of patent 7 years.

To all whom it may concern:

Be it known that I, FRANK E. STAIR, a citizen of the United States, residing at South Bend, in the county of St. Joseph and State of Indiana, have invented a new, original, and ornamental Design for a Lamp, of which the following is a specification, reference being had to the accompanying drawing, forming part thereof.

In the drawing,—

Figure 1 is an elevation of the lamp showing my new design, and

Fig. 2 is a plan view thereof.

I claim:

The ornamental design for a lamp, as shown.

FRANK E. STAIR.
